POULTRY-PAN-CLEANING DEVICE.

Application filed August 26, 1926. Serial No. 131,600.

This invention relates to a cleaning device for trays, particularly those used in the cages of poultry houses.

The chief object of the invention is to expeditiously, sanitarily and efficiently clean refuse receiving trays of the refuse deposited thereon.

The chief feature of the invention consists in providing a portable compartment with scraping or cleaning means within the same which is so fashioned that while the tray to be cleaned is positioned within the compartment the scraping or cleaning means is inoperative but becomes operative upon the withdrawal 15 of the tray and automatically whereby the latter is cleaned of the refuse deposited thereon, which refuse is deposited thereby in the lower portion of the compartment.

Another feature is that the upper portion 20 of the compartment is made wider than the lower portion so as to receive the scraping or cleaning means, and also shallow so that such wider portion can pass between lower and upper rows of feeding troughs which are attached to the cages.

The full nature of the invention will be understood from the accompanying drawings and the following description and claims:

In the drawings Fig. 1 is an end elevation 30 of a portable cleaner showing the same positioned in an aisle between two tiers of cages and clearing projecting portions thereof. Fig. 2 is a side elevational view with parts broken away to show the cleaning mechanism in side elevation. Fig. 3 is a perspective view 35 of a portion of the scraping or cleaning means and one supporting bar, parts being broken away, and showing said scraper and cleaning means in elevated non-scraping position as the supporting bar is moving inward and has almost reached the position shown in Fig. 2. Fig. 4 is a perspective view of a portion of what appears in Fig. 3, showing the scraping means in a downward and scraping position immediately after the supporting bar has reached its inward limit of movement and has started on its outward or withdrawal movement. Fig. 5 is a vertical transverse section through the upper part of the device, parts being broken away and parts shown by dotted lines, and showing the scraping means in its upper or non-scraping position as in Figs. 2 and 3. Fig. 6 is a longitudinal vertical section through the device

on line 6—6 of Fig. 1 showing the tray, tray-carrying frame and scraping means in their position as the tray and frame are being withdrawn, parts being broken away. Fig. 7 is a longitudinal vertical section of the upper right hand corner of the mechanism 55 shown in Figs. 2 and 6, showing the position of the scraping frame as it is being moved upward at the beginning of the introductory movement of the tray and tray supporting frame. Fig. 8 is a central transverse section 60 of the upper left hand corner of the compartment as shown in Fig. 5, but on a larger scale, wherein the scraping frame is in elevated position. Fig. 9 is the same, wherein the scraping frame is in scraping position as the tray and tray frame are being withdrawn, as shown in Fig. 6. Fig. 10 is a transverse vertical section of the tray supporting frame 65 centrally broken away.

In the drawings 10 indicates a tier of cages, 75 each cage being provided with a feeding trough 11 and a refuse supporting tray 12, the same being detachable with respect to the cage and said tray 12 is provided with three sides 13 so that it may be readily introduced into the cage and withdrawn therefrom. In the aisle formed between the cages there is adapted to pass a cleaning device in the form of a compartment 14 having an upper portion with upwardly and outwardly 80 inclined sides 15 forming the cleaning chamber above and appreciably wider than the refuse receiving portion of the compartment. The cleaning device by the arrangement 85 shown is adapted to pass between the several tiers and between those forming narrow aisles 90 with a minimum clearance and yet have the portion wide enough to clean the wide trays and also pass between upper and lower rows of troughs 11.

The portable cleaner includes a plurality of supporting wheels 16 and caster wheels 17 and associated with the same is an anchorage device 18. The upper compartment portion 20 includes a tray receiving aperture 21 and 100 slidably mounted therein is a tray supporting frame 22 having the exposed handles 23, whereby said frame can be moved into the compartment and withdrawn therefrom as desired. Said frame preferably at each side 105 has a cam bar 24 having at its inner end a bevel surface 25 inclined upwardly from the end and at the other opposite end a bevel

surface 26 inclined downwardly from the end. Slidably mounted for movement in a plane substantially transverse to the plane of the tray supporting frame movement is a scraping or cleaning frame comprising the vertical bars 27 connected by the transverse bars 28. A pair of brackets 29 secured to the wall of the compartment slidably support said frame bars 27 and spring means 30 is associated therewith for yieldingly supporting the scraping mechanism. Each of the bars 27 carries at its lower end a roller 31 and said roller in the movement of the tray supporting frame 22 into the compartment is engaged by the inclined cam surface 25 and is caused to ride upon the upper portion of the same and track bars 24, as shown in Fig. 7. When the tray supporting frame is fully positioned within the compartment, that is, to the extent of its possible movement, the roller 31 passes off of the horizontal track bars 24 and is in position to be engaged by the downwardly inclined cam surface 26 upon the retraction of the tray supporting frame. When this occurs the rollers engage said surfaces 26 and travel along the under sides of the track bars 24 and thus the scraping mechanism is drawn down to the lower position as shown in Fig. 4, whereas in the entering movement of the tray supporting frame the scraping mechanism is maintained elevated as shown in Figs. 3 and 5.

The tray scraping means comprises a plurality of scraping plates 40 positioned side by side in overlapped relation and each is supported by a stem 41 slidably mounted in aligned relation in the guide and transverse connecting members 28. Suitable spring means 42 provide a yielding mounting therefor. If desired, a single plate may be substituted for the aforesaid multiple and staggered plates. Also supported by the vertical movable bars 27 and in parallel relation, are the guide bars 43, the same being in spaced relation to each other and between and by said bars the scraping plates 40 are guided in their vertical movements.

The scraping or cleaning means is maintained in its upper and non-cleaning position, as shown in Fig. 5, by springs 30 and the rollers 31 riding up on the cam surface 25 at the ends of the bars 24 on the sides and forming a part of the sliding frame 22, as seen in Fig. 7. The tray 12 which has been removed from a cage filled with refuse is placed on the sliding frame 22 and they are pushed horizontally into the compartment, said frame sliding on the stationary angle bar supports 122 as seen in Fig. 5. As the tray and its frame support is pushed inward the scrapers 40 are maintained in their upper position as shown in Fig. 5, and, therefore, are inoperative for cleaning during such intermediate movement. But after the tray and its supporting frame have been pushed in to their inward limit of

movement, somewhat beyond the position shown in Fig. 2, the scraper frame is forced downward to the position shown in Fig. 6, as the tray and supporting frame are withdrawn by the cam surfaces 26 of the bars 24 which force the scraping frame down to its limit of movement, as seen in Fig. 9. This movement of the scraping frame causes the lower end of the scrapers 40 to engage the bottom of the pan or tray 12 and, as seen in Fig. 6, they scrape the contents of the pan or tray out as it is withdrawn and discharge the refuse over the inner open end of the pan or tray 12, as indicated in Fig. 6, down into the refuse receptacle 114 that is in the rear end of the lower narrow portion 14 of the compartment. As indicated in Fig. 2, said receptacle 114 is held in place by the pin 115 on said receptacle, and hook 116 pivoted on the compartment and when released the refuse receptacle can be removed from the compartment. The invention is, however, not limited to any particular construction of the refuse receptacle in the lower part of the compartment. The springs 42 on the upper ends of the stems 41 of the scrapers 40 yieldingly hold the scrapers in vertical position so as to permit them to accommodate themselves to any unevenness in the surface of the pan or tray being scraped. Said springs 42 in their neutral condition hold the scrapers as shown in Fig. 5.

The invention is not limited, necessarily, to the use of scrapers, as other cleaning means might be mounted substantially in the same way as the scrapers 40 for engaging the bottom of the pan or tray and cleaning out the refuse therefrom as the tray and its support are withdrawn, as indicated in Fig. 6.

The invention claimed is:

1. A poultry tray cleaning device including a tray receiving compartment, a tray supporting frame slidable therein, and cleaning means mounted in said compartment reciprocable towards and from the tray supporting frame for cleaning a tray on said frame as the latter is moved with reference to the compartment and cleaning means.

2. A poultry tray cleaning device substantially as set forth in claim 1, with means on the tray supporting frame for engaging and moving said cleaning means downward into cleaning position as the tray supporting frame is being withdrawn out of the compartment.

3. A poultry tray cleaning device substantially as set forth in claim 1, with means on the tray supporting frame adapted to engage and support the cleaning means in an upper non-cleaning position as said frame is being moved inward and for forcing the cleaning means into cleaning position as the frame is being withdrawn.

4. A poultry tray cleaning device substantially as set forth in claim 1, said cleaning means including rigid scraping plates adapt-

ed to engage the bottom of a tray on said tray supporting means for scraping out the refuse in said tray.

5. A poultry tray cleaning device substantially as set forth in claim 1, the tray supporting frame consisting of a frame slideable in said compartment, and cam bars secured to the sides thereof and each bar provided at its inner end with a beveled surface on the upper side thereof and on its outer end with a beveled surface on the lower side thereof and laterally projecting rollers on the cleaning means adapted to engage said bars so that as the frame is introduced into the compartment said rollers will ride upon said bars and elevate and maintain in elevated non-cleaning position said cleaning means, and when said frame is being withdrawn said rollers will move under said bars and force said cleaning means downward into cleaning position.

20 6. A poultry tray cleaning device substantially as set forth in claim 1, said cleaning means including a vertically disposed frame with vertical end bars, means secured to the walls of the compartment in which the end bars of said frame are vertically movable so

as to hold said cleaning frame over the tray supporting frame, and independent cleaning members yieldingly mounted vertically in said cleaning frame in position to engage the tray for cleaning the same when the cleaning frame is in its lower position.

25 7. A poultry tray cleaning device substantially as set forth in claim 1, said cleaning means including a vertically disposed frame with vertical end bars, means secured to the walls of the compartment in which the end bars of said frame are vertically movable so as to hold said cleaning frame over the tray supporting frame, independent cleaning members with individual stems extending upwardly therefrom and reciprocable through said cleaning frame, and a spring mounted on the upper end of each of said stems for yieldingly supporting the cleaning members so as to adapt them for cleaning irregular surfaces.

In witness whereof, we have hereunto affixed our signatures.
